UNITED STATES PATENT OFFICE

167,214

MILK CONTAINER JUG

Samuel Lapin, New York, N. Y.

Application December 13, 1948, Serial No. 150,129

Term of patent 3½ years

(Cl. D44—21)

To all whom it may concern:

Be it known that I, Samuel Lapin, a citizen of the United States, residing at 1760 Third Avenue, New York, in the county of New York and State of New York, have invented a new, original, and ornamental Design for Milk Container Jug, of which the following is a specification, reference being had to the accompanying drawing, constituting a part hereof.

Fig. 1 is a perspective view of milk container jug in an upright position, showing my new design.

Fig. 2 is a perspective view of the jug when disposed in a tilted position.

Fig. 3 is a side elevational view thereof.

The dotted line showing of the milk container in Figs. 1 and 2 is for illustrative purposes only.

I claim:

The ornamental design for milk container jug, substantially as shown and described.

SAMUEL LAPIN.
